UNITED STATES PATENT OFFICE.

JOHN A. GRIFFIN, OF LOS ANGELES, CALIFORNIA.

SECTIONAL REINFORCED-CONCRETE POLE.

1,069,328.

Specification of Letters Patent. Patented Aug. 5, 1913.

Application filed July 13, 1911. Serial No. 638,358.

To all whom it may concern:

Be it known that I, JOHN A. GRIFFIN, a citizen of the United States, residing at Los Angeles, in the county of Los Angeles and State of California, have invented new and useful Improvements in Sectional Reinforced-Concrete Poles, of which the following is a specification.

This invention relates to certain new and useful improvements in sectional reinforced concrete poles, and the object of the invention is to provide a pole formed of sections which are molded or made at a factory, and then transported to the point or points where the poles are to be erected.

The object of the invention is to provide improved and novel means for securing the sections relative to each other to form or constitute the pole.

In the drawings: Figure 1 is a perspective view of a pole constructed in accordance with the present invention showing the same in the process of erection, Fig. 2 is a side elevation partly in section, and Fig. 3 is a section on the line 3—3 of Fig. 2.

In accordance with the present invention I provide a series of sections 1 which are of hollow annular or cylinder-like form each being provided with a series of longitudinal spaced perforations 2.

3 designates a cement or other foundation or base which is molded with a series of vertical rods 4 embedded therein and having their upper ends extending thereabove, 35 the rods 4 projecting into the base 3 so as to receive a firm and rigid foothold therein. The rods 4 are of somewhat flexible character, that is to say, they can be bent with comparative ease to form accurate right angles with the base 3 so that the sections 1 may be threaded onto the rods 4 by passing the latter through the perforations 2 in said sections.

In proceeding in accordance with the present invention the rods 4 are sprung apart or bent at their upper ends so as to register with the perforations 2 in the lowermost section 1, after which the latter is threaded onto the rods 4 and is moved downwardly 50 to a position where it engages the base 3 as depicted in Fig. 2, after which wet grout or cement is poured into the perforations 2 to a point flush with the top of the lowermost section 1. The rods 4 are then tied by 55 means of a wire structure composed of a series of wire strands 5 which connect dia-

metrically opposite rods 4, which provide additional reinforcement for the rods 4. A series of wire connections 6 are passed about and firmly secured to the adjacent rods 4, 60 the connections 6 extending about the peripheral portions of the rods as clearly depicted in Fig. 3 of the drawings.

After the lowermost section has been positioned as above described and the wire binding or tying means for the rods 4 have been applied in the manner above set forth, and the cement has been poured into the perforations 2, the next section is then threaded onto the rods 4 in a manner just 70 described in connection with the lowermost section, it being understood that the wire binding or tying means composed of the wires 5 and 6 will permit the rods 4 to be moved outwardly from points above the 75 lowermost section 1 so as to have the next section threaded thereonto, after which the operation described in connection with the lowermost section is repeated.

7 designates holes which are provided in 80 the sections to receive steps.

It will be seen from the above that the rods 4 are continuous extending from the foundation to the top of the pole, and since they are joined or connected by the wires 5 and 85 6 at intervals occurring at the joints between adjacent sections, and since the cement when hardened causes the various parts to be firmly and rigidly related, the pole when completed presents one possessed 90 of great strength and durability and by reason of being formed hollow, effects a saving in the material of which the poles are formed.

If desired the perforations may be made 95 of comparatively large diameter, so that if very stiff or rigid rods 4 are employed, same need not be sprung apart to as great an extent as in cases where the perforations are of small diameter. Of course when the 100 pole is formed of equal diameter from top to bottom, as distinguished from the tapering form depicted in the drawings, the rods 4 are not required to be sprung apart at all, since they will then align with the perforations in the sections.

8 designates concrete filler which occupies the space between the ends of adjacent sections to act as a bond.

In cases where the poles are used to support telephone or telegraph wires, a cross arm or cross arms, of wood, concrete, or

other material can be attached to the poles at the desired height by bolting, clamping or by any other suitable means. When the poles are of extreme length, or short rods 5 only are available, they may be spliced to form continuous rods. Again, by using short rod sections which are connected, the rods can be of decreased diameter toward the top of the pole, which effects a great 10 saving since the bending stress of the pole reduces as the top of the same is approached. The wire sections may be connected by wiring, hooking, bolting or by any other suitable means or method of joining the same 15 together.

What is claimed is:

1. A concrete pole including a base having a series of spaced vertical rods secured thereto which rods incline toward each other 20 at their upper ends, a series of independent sections each having longitudinal perforations therein which extend through the tops and bottoms thereof, the sections being threaded onto said rods and arranged in 25 superposed order, binding means between the rods at the joints between the ends of adjacent sections, the binding means acting to draw the rods inwardly at the upper end of a lower section and to center same 30 in the perforations of said lower section and

also to allow the rods beyond the said upper end of the lower section to be moved outwardly to receive the next upper section, and a filler of grout occupying the perforations of the sections and surrounding the 35 rods and the binding means where the latter occurs between the ends of adjacent sections.

2. A concrete pole including a base having a series of vertical rods secured thereto, 40 a series of hollow independent sections each having a series of spaced longitudinal perforations therein of considerably greater diameter than the diameter of the rods, said sections being threaded onto the rods, grout 45 in the perforations surrounding the rods, tying wires which extend across the interiors of the sections and are connected to the rods to draw and hold same inwardly, and grout inclosing the tying wires where the latter 50 cross the section ends and being in engagement with the adjacent ends of adjacent sections.

In testimony wheroft I have hereunto set my hand in presence of two subscribing witnesses.

JOHN A. GRIFFIN.
